LE ROY H. KIESLING, OF BROOKLYN, NEW YORK

ELEVATOR TRACK MOUNTING

Application filed July 17, 1931. Serial No. 551,388.

This invention is a novel elevator track mounting and relates more particularly to a construction for adjustably mounting the vertically extending track of an elevator upon the wall or walls of the elevator shaft.

The general object of the present invention is to improve and simplify known means of mounting elevator tracks, as well as to cheapen the cost of construction thereof and to simplify the labor of erecting and installing the apparatus, without impairing efficiency and durability.

The illustrated embodiment is shown applied to an elevator of the type used, for example in office buildings wherein the guide means consists usually of a single track at each of the two opposite sides of the shaft, such track being of T-shape with its flange clamped to the mounting means and its web projecting inwardly and forming the actual guide on which the sliding shoes of the elevator car contact and run. In this or equivalent elevator construction the present invention has the advantage that the opposite pair of tracks are readily and effectively mounted, adjusted and secured at the place of use by the constructor without the need of drilling or machining of other operations and with minimum difficulty in properly spacing, alining and clamping the tracks in place.

Other and further objects and advantages of the invention will be apparent to those conversant with the subject matter to which the invention relates. To the attainment of such objects and advantages the present invention consists in the novel elevator track mounting, and the novel features of combination, arrangement, construction and detail herein described or illustrated.

In the accompanying drawing Figure 1 is a top plan view, partly broken away, of an elevator track mounting embodying the present invention, with one of the shaft walls shown in section, and the illustrated parts being understood to be symmetrically duplicated at the opposite shaft wall.

Fig. 2 is an interior elevation view of the parts shown in Fig. 1.

Fig. 3 on a smaller scale is a right elevation view, with certain parts shown in section.

In the drawing corresponding numbers designate the same parts in the several figures.

The illustrated track member 10, at each side of the elevator shaft, may be of any convenient shape, such as the usual T-shape. Thus the track member 10 is shown as composed of a web or track portion 11 having smooth or machined opposite faces 12 upon which run the shoes of the car, with one or two outer flanges 13 by which the track member is mounted and clamped permanently in place. The track member 10 will be understood to extend continuously vertically through the height of the building, with tongue and groove or other convenient joints between successive sections thereof. The elevator shaft wall 14 may be composed of any suitable building material, brick, cement or the like. As indicated in Fig. 3 a series of mounting means 15, 15^a etc. for the guiding track 10 is indicated, spaced for example 10 feet apart vertically.

The details of the elevator track mounting hereof will now be described. A horizontal or hanger plate 16 of structural steel or the like is shown as permanently and firmly attached to the shaft wall 14 by means of through bolts 17 which may extend outwardly to a convenient anchoring position.

Extending inwardly from the hanger plate are shown two threaded members or posts 18, preferably at the same level, and spaced substantially apart horizontally. These threaded posts constitute part of the adjustable mounting means for the track member 10. On each of the threaded posts is shown an outer nut 19. Contacting against the two nuts 19 is a cross bar 20 against which the flanges 13 of the track member are rigidly held. The cross bar 20 near each end is shown as formed with a perforation or other aperture 21. These may be circular apertures preferably somewhat larger than the posts so as to fit loosely, but they might be U-shape recesses extending inwardly from the ends of the bar.

Opposed to the outer nuts 19 are a pair of inner nuts 22, one on each threaded post, these being arranged so that when tightened

they bear upon the cross bar to clamp and lock it permanently in place. Preferably the nuts 22 are arranged not only to clamp the cross bar upon the threaded posts, but also to clamp the flanges of the T rail or track upon the cross bar. A convenient fitting for this purpose is a curved clip 23 arranged beneath each nut 22 and arranged to bear at one side directly upon the cross bar and at the other side directly upon the track flange.

By this arrangement when the parts are adjusted and the nuts tightened a rigid permanent structure is secured. The track is readily adjustable inwardly and outwardly by loosening and tightening the nuts 19, 19 and 22, 22 respectively. Indeed, in case it is necessary to tilt slightly the position of the track member 10 one pair of nuts 19, 22 may be adjustable relatively to the other pair. In this way a very accurate setting of the guiding track is readily obtainable and rigidly securable, with the two opposite tracks in exact alinement with each other. In dotted lines in Fig. 1 is indicated an adjustment wherein the track is adjusted bodily inward and at the same time tilted slightly to one side. In this way any unevenness in the parallelism of the opposite walls can be corrected and the tracks trued up relatively to each other and the car.

The present invention wholly dispenses with the common practise of inserting thin plates and shims behind the flanges of the track and endeavoring by trial and substitution to attain the correct position for the track.

In cases where not only the car but the counterweight may be guided by adjustable tracks the present invention may be used for both.

There has thus been described an elevator track mounting embodying the principles and attaining the objects and advantages of the present invention. Since various matters of combination, arrangement, construction and detail may be modified without departing from the principles of the invention it is not intended to limit the invention to such matters except so far as set forth in the appended claims.

What is claimed is:

1. An elevator track mounting comprising a hanger plate on the shaft wall, horizontally spaced threaded posts projecting inwardly from the plate, a cross bar having apertures fitting said posts, a vertical track member bearing on the inner side of the bar, threaded nuts on said posts outside of and bearing on said cross bar, and threaded nuts on said posts inside of and bearing on said track member and bar to hold them in rigid relation.

2. A mounting as in claim 1 and wherein the cross bar apertures loosely fit the post and between the cross bar and each inner nut is

an apertured clip overlying the track flange at one side.

3. In combination with a vertically extending T-shape elevator track, and the elevator shaft wall, a series of vertically spaced 70 mountings, each comprising an apertured cross bar, a pair of threaded posts projecting from the wall and engaging the apertures of the cross bar, and means for adjusting and clamping the cross bar upon each 75 post, and clamping the track flange to the cross bar.

In testimony whereof, this specification has been duly signed by:
